UNITED STATES PATENT OFFICE.

PHILIP MACKENZIE, OF SAN FRANCISCO, CALIFORNIA.

PAWL-AND-RATCHET POWER APPLIANCE.

Application filed May 17, 1922. Serial No. 561,555.

To all whom it may concern:

Be it known that I, PHILIP MACKENZIE, a citizen of Canada, residing at the city and county of San Francisco and State of California, have invented new and useful Improvements in Pawl-and-Ratchet Power Appliances, of which the following is a specification.

This invention relates to pawl and ratchet power appliances, especially intended for use in connection with jacks, capstans and the like. The object of the invention is to simplify and improve the construction and operation of a mechanism of this sort.

In the type of device under consideration there is a rocking pawl lever which actuates a pair of pawls for driving a ratchet wheel, the wheel being advanced one or more teeth on each forward movement of the lever and a similar distance on the backward movement of the lever. The present improvements contemplate the provision of mechanism for controlling the pawls so that they may be quickly and easily changed from their forward driving position to their reverse driving position, even when the ratchet wheel is under full load. Also both pawls may be thrown out to allow the ratchet wheel to be turned freely. I have also embodied novel means for taking up thrusts imposed upon the bearings of the pawl lever.

One form which my invention may assume is exemplified in the following description and illustrated in the accompanying drawings, in which—

Fig. 1 shows a side elevation, partly in section, of mechanism embodying my invention.

Fig. 2 shows a detail view in side elevation of the pawl mechanism in position for driving the ratchet wheel in a reverse direction from that shown in Fig. 1.

Fig. 3 shows a detail of a novel form of spring employed for placing tension upon the pawls.

Fig. 4 shows a detail sectional view of the connections between the pawls and lever.

Figs. 5, 6 and 7 show different views of the pawl mechanism in position for releasing the ratchet wheel, one tooth at a time.

Fig. 8 shows a view of the pawl mechanism entirely disengaged from the ratchet wheel.

Referring in detail to the accompanying drawing, I have shown a frame 10 having a

ratchet wheel 11 journaled thereon, said ratchet wheel acting to operate a lifting or hoisting device. As here illustrated, the ratchet wheel is mounted upon a shaft 12 which carries a capstan 14, the latter being fitted with the usual winding rope 15. Pivoted on the frame to one side of the ratchet wheel is a pawl lever 16 to either side of the axis of which is connected a pawl 17 co-operating with the teeth on the ratchet wheel. Connected to each pawl is a spring wire 18 fixed to a post 19. Around each post is a coiled spring 20, the ends of which straddle the wire and are held against unwinding movement by a lug 21. Thus the spring wire may be put under tension in either direction without unwinding the coil.

Both posts 19 are fixed upon a plate 22 which pivots about an axis 23 and is controlled by means of a handle or arm 24. Pins or lugs 25 fastened to the frame are arranged at opposite ends of the movement of the arm 24 and serve to retain the latter in adjusted position. If the arm be moved to the position shown in Fig. 1, the spring wires are under tension to hold the pawls in engagement with the ratchet teeth, and therefore when the pawl lever is rocked the ratchet wheel is fed forwardly one or more teeth to each stroke. When the arm 24 is in the position shown in Fig. 2, the tension on the spring wires tends to force the pawls out of engagement with the ratchet teeth.

The inner pawl has a cam surface 26 to co-operate with a cam surface 27 on the outer pawl. Likewise, the outer pawl has a cam surface 28 to co-operate with a pivoted cam member 29. This cam member 29 is held inwardly by a spring 30 and a set screw 31 is provided for regulating the tension of the spring. Also a set screw 32 is arranged at the other end of the pivoted cam to assist in regulating the position of the said pivoted cam. A latch device 33 is provided for permanently holding the said pivoted cam out of contact with the outer pawl member.

To enable the device to be operated in a reverse direction, one tooth at a time, the tension on the springs on the pawls is reversed, as shown in Fig. 2. If the lever be in rearward position, as shown in said Fig. 2, the outer pawl will be out of engagement with its tooth, but its position will be such as to retain the inner pawl in engagement with the ratchet wheel so as to restrain the

load. As the lever starts to move forwardly, as shown in Fig. 5, the outer pawl will be advanced and the inner pawl will recede. As the outer pawl comes forwardly, it will be moved into engagement with a tooth of the ratchet wheel by the action of the pivoted cam 29, and at the same time the inner pawl, resisting the load, will remain engaged with the ratchet wheel. When the lever reaches its forward position, as shown in Fig. 6, the outer pawl has fully engaged a ratchet tooth and taken up the load, leaving the inner pawl free to move out of engagement with the ratchet wheel under the influence of its spring. As the lever starts to move rearwardly, as shown in Fig. 7, the outer pawl is receding while resisting the load, and the inner pawl is advancing free of the ratchet teeth. As the two pawls approach their operating cam surfaces contact and force the inner pawl into engagement with a ratchet tooth. Just before the lever reaches its extreme rearward position, shown in Fig. 2, the inner pawl has taken up the load, leaving the outer pawl free to move out of engagement with the ratchet wheel.

If the pivoted cam 29 be held by the latch device 33 out of engagement with the cam surface on the outer pawl, then the action of the spring wires 18 will be to lift both pawls out of engagement with the ratchet teeth and allow the said ratchet wheel to be turned freely in either direction, as shown in Fig. 8.

The above described construction permits the change from forward drive to reverse drive to be made even when the ratchet wheel is under full load, since it is only necessary to move the arm or handle 24 from one position to the other and to set the pivoted cam 29 accordingly.

Another improvement embodied in the present structure is the provision of novel means for taking up the thrusts imposed upon the bearings of the pawl lever. This is in the form of a segmental plate 34, pivoted at 35 and co-acting at its forward position with a semi-circular plate 36, the latter being fixed upon the axis of the pawl lever. The rear or pivoted end of the segmental pawl 34 abuts against a thrust member 37 removably fitted into the corner of the frame. Thus the thrusts on the bearings of the pawl lever are transmitted to the corner of the frame and the parts exposed to the greatest wear are removable and replaceable.

The manner in which I attach the pawls to the pawl lever is also advantageous. The pawl lever has a stub shaft or boss 38 which has a segmental portion 39 cut out of its front. Longitudinal recesses 40 are formed in the boss at each end of the cutaway portion and into these recesses the pins 41, forming the pivots of the pawls, are in-

serted. Then a filling strip 42 is placed between the protruding pawls and one end of the cutaway segmental portion and said strip is fastened in place by means of screws 43 inserted through one end of the boss. One end of the boss or stub shaft is squared, as shown at 44, to receive the pawl lever.

Various changes in the construction and arrangement of the several parts herein shown and described may be employed without departing from the spirit of the invention as disclosed in the appended claims.

Having thus described my invention, what I claim and desire to secure by Letters Patent is:

1. In a pawl and ratchet power appliance, a frame, a ratchet wheel journaled thereon, a pawl lever mounted for rocking movement on the frame, a pawl pivoted to the pawl lever on either side of the axis thereof and cooperating with the teeth on the ratchet wheel, means for retaining the pawls yieldingly in engagement with the teeth of the ratchet wheel for driving the wheel forwardly and means for optionally causing alternate disengagement and re-engagement of the pawls to permit the ratchet wheel to be reversed when under load, said last mentioned means comprising yielding means to exert an outward pressure on each of said pawls, co-acting cam surfaces between the two pawls to control the outward movement of the inner pawl, a cam surface on the outer pawl and a co-acting adjustable cam to co-operate therewith for the purpose of controlling the outward movement of the outer pawl.

2. In a pawl and ratchet power appliance of the character described, a ratchet wheel, a pawl lever, a pair of pawls thereon for actuating the ratchet wheel and spring means for exerting pressure on the pawls optionally in opposite directions comprising a spring wire for each pawl, a post to which the wire is fixed, a coil surrounding the post and having its ends engaging at opposite sides of the wire and means to hold one of the ends stationary when the other end is acted upon by the wire.

3. In a pawl and ratchet power appliance of the character described, a ratchet wheel, a pawl lever, a pair of pawls thereon for actuating the ratchet wheel and spring means for exerting pressure on the pawls optionally in opposite directions comprising a spring wire for each pawl, a post to which the wire is fixed, a coil surrounding the post and having its ends engaging at opposite sides of the wire, means to hold one of the ends stationary when the other end is acted upon by the wire and means to swing the posts in unison to reverse the direction of the tension applied by the wires upon the pawls.

4. In a pawl and ratchet power appliance,

- a frame, a ratchet wheel journaled thereon, a pawl lever mounted for rocking movement on the frame, a pawl pivoted to the pawl lever on either side of the axis there-
5 of to co-operate with the teeth on the ratchet wheel, means for yieldingly retaining the pawls in engagement with the teeth of the ratchet wheel for driving the wheel forwardly and means for causing the pawls
10 to disengage and re-engage alternately with the ratchet wheel for reversing the latter under load, said reversing mechanism comprising yielding means tending to force the pawls out of engagement with the teeth of
15 the ratchet wheel, a cam co-operating with the outer pawl to cause the latter to engage a tooth near the termination of its advance-
ment and co-operating cam surfaces between the inner and outer pawls to cause the inner
20 pawl to engage a ratchet tooth near the termination of its advance stroke, said cam surfaces being out of contact on the receding stroke of each pawl, said first-mentioned cam mechanism being movable to entirely clear the outer pawl whereby to permit both 25
5. In a device of the character described, a ratchet wheel, a rocking pawl lever, a pawl pivoted to said lever at each side of the axis 30 thereof for actuating the ratchet wheel, said lever having a boss provided with a cutaway portion to receive the pawls, pins on each side of said pawls fitting in recesses at the ends of the cutaway portion and a removable filling strip between the pawls and one end of the cutaway portion to retain the pawls in place. 35

PHILIP MACKENZIE.
